UNITED STATES PATENT OFFICE.

WALTER R. CAVNER, OF VENICE, ILLINOIS, ASSIGNOR TO COMMONWEALTH STEEL COMPANY, OF ST. LOUIS, MISSOURI, A CORPORATION OF NEW JERSEY.

CAR END FRAME.

1,073,663.

Specification of Letters Patent. Patented Sept. 23, 1913.

Application filed April 7, 1913. Serial No. 759,500.

To all whom it may concern:

Be it known that I, WALTER R. CAVNER, a citizen of the United States, residing at Venice, Illinois, have invented a certain new and useful Improvement in Car End Frames, of which the following is a full, clear, and exact description, such as will enable others skilled in the art to which it appertains to make and use the same, reference being had to the accompanying drawings, forming part of this specification, in which—

Figure 1 is an elevational view of my improved car end frame applied to the end of a gondola car. Fig. 2 is a side elevational view of the end portion of a gondola car, and showing my improved end frame applied thereto. Fig. 3 is a horizontal section taken on the line 3—3 of Fig. 1.

My invention relates to a new and useful strengthening and reinforcing end frame particularly adapted for gondola cars, although it will be readily understood that the frame may be made in various sizes so as to be combined with all forms of freight cars.

The principal object of my invention is to construct a strengthening and reinforcing end frame in one piece, preferably by casting, and which end frame is adapted to be applied directly to the end portion of a car body for the purpose of reinforcing the end wall thereof against all stresses and strains resulting from shocks or blows delivered from the exterior, and likewise all shocks and blows resulting from shifting loads within the car.

It is the ordinary practice to construct freight cars of the box and gondola type of wood or of sheet metal, and it is the purpose of my invention to construct a skeleton frame of metal and to apply the same directly to the end wall of the car for the purpose of reinforcing and strengthening the same and resisting such shocks and strains as the end portion of the car body ordinarily receives in service.

To the above purposes my invention consists in certain novel features of construction and arrangement of parts hereinafter more fully described and claimed.

As shown in the drawings, my improved reinforcing end frame comprises a base rail or member 10, a pair of vertically disposed end rails or uprights 11, a top rail or mem-

ber 12 and a pair of diagonally disposed intersecting rails or members 13 which are formed integral with the corners of the frame formed by the members 10, 11 and 12, and which intersect at a central point in said frame. The base member 10 is provided with an integral, horizontally disposed flange 10^a, which, when the frame is applied to the end of a car, rests directly upon and is preferably fixed to the end sill "A" of the car. The vertically disposed members 11 are provided with rearwardly projecting flanges 11^a, which bear directly against and are fixed to the ends of the side walls "B" of the car body. The top member 12 of the frame is provided with an integral, inwardly projecting flange 12^a, which overlies the top of the end wall "C" of the car body. The diagonally disposed intersecting members 13 are provided on their outer faces with outwardly projecting reinforcing ribs or flanges 13^a, which are preferably highest at the point where they intersect, and gradually decreasing in height toward the corners of the skeleton frame.

When my improved end frame is applied for use the base flange 10^a rests directly upon the end sill "A" of the car, the upright members 11 engage the corners of the car body, the top rail 12 engages the upper edge of the car end wall and the members 13 lie directly against the outer face of the car end wall. By such construction the entire end of the car is reinforced and strengthened against shocks and crushing stresses delivered from the exterior, and also shocks and blows delivered from the interior of the car as a result of shifting loads.

The upright members 11 provided with flanges 11^a protect the corners of the car body, and likewise the top rail 12 provided with the integral flange 12^a protects the upper edge of the end wall of the car.

My improved end frame is preferably formed in a single piece of metal and when applied for use forms a very strong and rigid reinforcement for car ends.

It will be readily understood that minor changes in the size, form and construction of the various parts of my improved end frame can be made and substituted for those herein shown and described without departing from the spirit of my invention, the scope of which is set forth in the appended claims.

I claim:

1. A car end reinforcing member having a pair of diagonally disposed intersecting reinforcing ribs which extend from the upper corners of the car to the lower corners thereof.

2. A car end reinforcing member comprising a rectangular frame adapted to engage the marginal edges of the car end wall, and a pair of diagonally disposed integral members extending between the corners of said frame.

3. A reinforcing end frame for cars, comprising a base rail, a pair of upright members, a top rail, and a pair of diagonally disposed intersecting rails, all of which parts are formed integral.

4. A reinforcing member for car ends, comprising a rectangular frame, diagonally disposed intersecting rails integral with said frame, and strengthening ribs integral with said diagonally disposed rails.

5. A reinforcing end frame for cars, comprising a flanged base member, a pair of flanged upright members, a flanged top member, and a pair of flanged diagonally disposed intersecting member extending between the corners of said frame.

6. A reinforcing end frame for cars, comprising a base member, an outwardly pro-

jecting flange integral therewith, a pair of upright members, a top member, rearwardly projecting flanges on said upright members, and the top member, and a pair of diagonally disposed intersecting flanged members extending between the corners of the frame.

7. As a new article of manufacture, a reinforcing frame for the ends of cars comprising a rectangular frame adapted to engage the marginal edges of the car end wall, and a pair of diagonally disposed rails extending between the corners of said frame, all of which parts are cast integral.

8. As a new article of manufacture, a car end reinforcing member comprising a rectangular frame provided with marginal flanges adapted to engage parts of the car to which the frame is applied, and a pair of diagonally disposed members extending between the corners of the frame, all of which parts are formed integral.

In testimony whereof I hereunto affix my signature in the presence of two witnesses, this 2nd day of April, 1913.

WALTER R. CAVNER.
